United States Patent Office.

F. S. PEASE, OF BUFFALO, NEW YORK.

Letters Patent No. 65,595, dated June 11, 1867.

IMPROVED BLAST APPARATUS FOR CARBURETTERS.

The Schedule referred to in these Letters Patent and making part of the same.

TO ALL WHOM IT MAY CONCERN:

Be it known that I, F. S. PEASE, of Buffalo, in the county of Erie, and the State of New York, have invented a new and useful Improved Blast Apparatus for Carburetters; and I do hereby declare the following to be a full, clear, and exact description of the same, sufficient to enable others skilled in the art to which it appertains, to construct and use the same, reference being had to the accompanying drawings, making part of this specification.

This improvement consists of a double bellows, (or a series of them,) operated through the medium of rods, by eccentrics on a horizontal shaft, the eccentrics being so arranged as to divide the circle and operate the bellows consecutively, making an effective stroke in each direction as the lower bellows are double with a partition, each section having connection by a valve opening upwards with the reservoir bellows above.

In the drawings are shown three double lower bellows A, each of the three having a partition, B, dividing it in fact into a pair of bellows, the lower board C oscillating upon a horizontal axis or pivot, D, so that each motion is made effective in delivering a body of air into the upper reservoir bellows E.

The motions of the bellows are produced by eccentrics F on the revolving shaft G, the rods H connecting the eccentrics with the bellows. The eccentrics are so arranged upon the shaft that they divide the circle, that is, when, as in the drawing, there are three of them. The eccentrics are so set upon the shaft that they follow in regular consecutive series, and operate upon the bellows to produce a constant blast.

The sides or expanding and contracting portions of the bellows are made of wooden plates, united to each other and to the upper and lower boards by means of elastic membranes or strips, so that they will not bag out when a blast is applied but will bear considerable pressure. Cranks may be substituted for the eccentrics, and the shaft may have a reciprocating rotary motion or a complete revolving motion.

Having described my invention, what I claim as new, and desire to secure by Letters Patent, is—

1. The double bellows A, so constructed that the sections are reciprocally operated by the same impulse from crank or eccentric on a rotary or vibrating shaft, substantially as described.
2. The combination of the rotary or vibrating shaft G, provided with cranks or eccentrics, the connecting rods H, and series of double bellows A A, substantially as described.

To the above specification of my improvement I have signed my hand this 19th day of March, 1867.

F. S. PEASE.
